UNITED STATES PATENT OFFICE

HENRY J. STORK, OF ARLINGTON, NEBRASKA

LUBRICANT-DISPENSING DEVICE

Application filed November 29, 1927. Serial No. 236,457.

The invention relates to a lubricant dispensing device, and has for its object to provide a device of this character particularly adapted for use in garages, and provided with 5 a plurality of receptacles having pistons therein, which pistons are provided with rack bars, with which a rotatable gear meshes whereby upon rotating said gear one piston will be forced downwardly, and the other 10 piston simultaneously moved upwardly, whereby when lubricant is discharged from one cylinder, it may be sucked into the other cylinder for a subsequent dispensing operation.

15 A further object is to provide a supply pipe leading from a lubricant supply tank and having branch pipes through either of which lubricant may be directed to either of the dispensing cylinders. Also to provide discharge 20 pipes leading from the cylinders.

A further object is to form the cylinders from transparent material whereby the liquid level therein may be observed, and to provide said cylinders with graduations whereby 25 the amount of lubricant in the cylinders may be easily ascertained.

With the above and other objects in view the invention resides in the combination and arrangement of parts as hereinafter set forth, 30 shown in the drawing, described and claimed, it being understood that changes in the precise embodiment of the invention may be made within the scope of what is claimed 35 without departing from the spirit of the invention.

In the drawing:

Figure 1 is a front elevation of the device, parts being shown in section to better illustrate the same.

40 Figure 2 is a side elevation of the device.

Figure 3 is a vertical transverse sectional view through another form of cylinder wherein a piston is controlled by a piston rod.

45 Referring to the drawing, the numeral 1 designates a base, which base has mounted thereon flanged cylinder bases 2 in which are disposed the lower ends of transparent cylinders 3. Cylinders 3 are preferably formed 50 from glass and provided with graduations 4,

whereby the amount of lubricant therein may be ascertained at all times. Disposed on the upper ends of the cylinders 3 is a flanged cap 5, forming a closure for the upper ends of the cylinders, and slidably mounted within the cylinders are pistons 6, which pistons are provided with upwardly extending piston rods 7 having racks 8 on their inner adjacent sides.

Extending upwardly from the cap 5 is a bracket 9 in the arms 10 of which the piston rods 7 are slidably mounted, and rotatably mounted in the upper end of the bracket 9 is a transversely disposed shaft 11 having a gear 12 thereon, which gear meshes with the racks 65 8; therefore it will be seen that when the operator grasps the handle member 13 and rotates the gear 12, one of said piston rods and pistons will be forced downwardly and at the same time the other piston and piston rod 70 will be forced upwardly, and as a result of this operation lubricant within one of the cylinders will be forced outwardly through its discharge pipe 14 while lubricant will be sucked into the other cylinder through the lubricant supply pipes 15 according to which piston is moving upwardly; therefore it will be seen that 75 when the lubricant is dispensed from one cylinder, the other cylinder will be automatically filled, consequently a constant lubricant supply is maintained for dispensing purposes. Discharge pipes 14 are preferably provided with valves 16 for regulating the amount of lubricant and speed of delivery.

Supply pipes 15 are connected to the casing 80 17 of a three way valve 18 and a pipe 19 is connected to the casing 17 and leads to a lubricant storage tank 20, and it will be seen by referring to Figure 1, said three way valve 18 is in position where upon upward movement 85 of one of the pistons 6, lubricant will be sucked into its cylinder 3, as the lubricant is discharged from the other cylinder 3, and after the lubricant is discharged from the cylinder 90 that is filled, the three way valve is manipulated whereby lubricant will be sucked into the emptied cylinder upon upward movement 95 of its piston. The cap 5 is preferably provided with an air vent 21 whereby air may exhaust from the upper ends of the cylinders 3, 100

thereby preventing the same from becoming air bound. Tank 20 is also provided with an air vent 22 for allowing passage of air during the filling of the tank and the pumping of lubricant therefrom, thereby preventing the same from becoming airbound or the formation of vacuum in said tank as lubricant is pumped therefrom,

Referring to Figure 3 a hand operated device is shown, which device operates substantially the same as one of the cylinders shown in Figure 1 and has its piston 6^a provided with a piston rod 7^a, and which piston rod is adapted to be forced downwardly for discharging lubricant from the cylinder 3^a through the discharge pipe 14^a. In this form a coiled spring 23 is provided which surrounds the piston rod 7^a and is interposed between the cap 5^a and the piston 6^a, thereby assisting in forcing the piston downwardly for discharging lubricant from the cylinder.

From the above it will be seen that a lubricant dispensing device is provided which is particularly adapted for use in dispensing lubricant in garages and the like, and one wherein not only the operator but the purchaser may see the amount of lubricant discharged into a crank casing or other point of discharge.

The invention having been set forth what is claimed as new and useful is:—

A lubricant dispensing device comprising adjacent cylinders formed from transparent material, discharge pipes carried by the lower ends of said cylinders, a lubricant supply pipe, branch lubricant supply pipes, valve means carried by said supply pipe at its point of connection with the branch pipes and forming means whereby lubricant may be directed through either branch supply pipe or simultaneously drained from both of said cylinders, pistons within said cylinders, piston rods carried by said pistons, said piston rods having their adjacent sides provided with racks, a bracket supported by the cylinders, said piston rods being slidably mounted in bearings of the bracket, and an operating gear carried by said bracket and meshing with the racks.

In testimony whereof I hereunto affix my signature.

HENRY J. STORK.
